US00D631469S

(12) **United States Design Patent**
Demskie et al.

(10) **Patent No.:** **US D631,469 S**
(45) **Date of Patent:** ** *Jan. 25, 2011

(54) **REMOTE CONTROL AND DISPLAY DEVICE**

(75) Inventors: **John Michael Demskie**, Prior Lake, MN (US); **Bruce William Gaunt**, Albertville, MN (US); **Stefan Reiley Freeman**, Minneapolis, MN (US); **Timothy James Morton**, Austin, TX (US)

(73) Assignee: **Remote Technologies, Inc.**, Shakopee, MN (US)

(*) Notice: This patent is subject to a terminal disclaimer.

(**) Term: **14 Years**

(21) Appl. No.: **29/355,580**

(22) Filed: **Feb. 10, 2010**

(51) **LOC (9) Cl.** **14-03**

(52) **U.S. Cl.** **D14/218**

(58) **Field of Classification Search** D14/174, D14/137-139, 151, 217, 218, 191-193, 167, D14/299, 168, 247, 455, 456; D13/168, D13/162-164; D21/512-517, 566; D10/104, D10/106; 345/169; 348/114, 734; 455/352-355, 455/151.1-151.4, 128, 347, 90.3

See application file for complete search history.

(57) **CLAIM**

The ornamental design for a remote control and display device, as shown and described.

DESCRIPTION

FIG. 1 is a perspective view of a remote control and display device showing our new design;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is a perspective view thereof in an alternate position of use.

In the drawings, the broken lines depict environmental subject matter only and form no part of the claimed design.
